UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A CARD-MOUNT.

SPECIFICATION forming part of Design No. 27,497, dated August 10, 1897.

Application filed May 8, 1897. Serial No. 635,743. Term of patent 7 years.

To all whom it may concern:

Be it known that I, JOHN P. ODGERS, a citizen of the United States, residing in Philadelphia, Pennsylvania, have invented a certain new and original Design for Card-Mounts, of which the following is a specification.

My design is shown in the accompanying drawing, which represents a face view of the card.

10 The leading feature of the design is the ornamentation of the border of the card. This border comprises an inner row of scallops *a* and an outer row of scallops *b*, each scallop containing a trefoil ornament *d*. The portion of the border between these edge scal-

lops has a striped effect, due to waved ribs *f*, which fill the spaces between the scalloped edges, as shown in the upper right-hand corner of the drawing.

I claim—

20 The design for a card-mount, substantially as described, and as shown in the accompanying drawing.

In testimony whereof I have signed my name to this specification in the presence of 25 two subscribing witnesses.

JOHN P. ODGERS.

Witnesses:

WILL. A. BARR,
F. E. BECHTOLD.
